UNITED STATES PATENT OFFICE

2,312,286

ORNAMENT FOR CHRISTMAS TREES AND
THE LIKEJoseph Reich, New York, N. Y., assignor to Elite
Hand-Painting Corporation, New York, N. Y.

Application January 29, 1941, Serial No. 376,439

4 Claims. (Cl. 41—10)

This invention relates to ornaments, particularly to an ornament to be used for a Christmas tree, and has for its main object to provide a device of this character of novel improved construction and of artistic novel effect.

Another object of this invention is to provide a device as characterized hereinbefore, which will have simple efficient securing means, whereby it may be easily and removably secured on a Christmas tree.

Still a further object of my invention is to provide a device of the type mentioned, which will be simple in construction, adapted to easy mass manufacturing and inexpensive in cost.

Other objects of this invention will be apparent as the specification of the same proceeds.

In the drawings forming a part of this specification and accompanying the same,

Fig. 1 is a front elevational view of my assembled novel ornament;

Fig. 2 is a side elevation thereof, and

Fig. 3 is a rear elevation indicating the same applied on a Christmas tree;

Fig. 4 is an elevational view of the main body or doll used as a basis for constructing my novel ornament, the blanks for the sleeves of the preferred dress to be made for my ornament being indicated adjacent to the arms of said doll or main body;

Fig. 5 is a sectional elevation of a tube used as a preferred form of removably securing my ornament on a Christmas tree or the like;

Fig. 6 is a plan view of a portion of a strand of textile threads to form the hair of the ornamental doll of my invention, the full strand, of which the indicated portion shown is to be cut, being indicated by dot and dash lines in an imaginary manner;

Fig. 7 is a plan view of a pair of wings to be used in building up my ornament;

Figs. 8 and 9 are rear views in two positions indicating the construction of the dress for my doll ornament;

Fig. 9a shows the blank to be used for the blouse or waist of the dress of my so-called angel doll ornament.

Figs. 10 and 11 are plan view and side elevational view, respectively, of a preferred method of mounting my ornament for storage or shipping;

Figs. 12 and 13 are front and end views, respectively, of an ornamental band with a crown to be used on the head of my ornament, and

Fig. 14 is a plan view of a band to be used as the belt for my ornamental doll;

Figs. 15 and 16 indicate the method of securing ornamental stars on the dress of my doll;

Fig. 17 is a perspective view of the securing tube shown in section in Fig. 5, and

Fig. 18 indicates the staples used for securing parts of my doll together.

My novel ornament for Christmas trees, and for other purposes, substantially is a doll, dressed and shaped like an angel, and having means associated therewith, whereby it may be easily and removably secured on the tip of a Christmas tree or any branch thereof.

Referring now to the drawings more in detail by characters of reference, the numeral 20 indicates my fully assembled dressed ornamental angel doll, in general, the same being built up of a base doll or body, generally indicated by the numeral 21, of a dress, generally indicated by the numeral 22, and having certain ornaments associated therewith, as will be more fully described hereinafter, and a pair of wings 23.

The basic body or doll 21 may have an appropriate body proper 24, a head 25, two arms 26, attached to the body 24 in any appropriate manner, and preferably in a movable jointed way, as indicated at 27, and having the hands 28.

A downward cylindrical extension 29 is added to the main body 24, being of considerably smaller diameter than the body, and the body preferably terminating in a cylindrical lower flange portion 30.

The dress of the doll is composed of a skirt portion 31, a blouse or waist portion 32, having a triangular extension 33, and the two sleeve portions 34.

The skirt 31 is outwardly flaring in a downward direction and may be secured to the waist portion 32 by the seam 35. It is cut from an appropriate piece of textile material, preferably of shining silk or the like, in a blank of obvious shape, the free edges 31a and 31b of which are secured together by a seam 36 in the rear of the dress. The blank of the waist or blouse is shown in Fig. 9a and it has the two side portions 37 and the mentioned triangular portion 33, and when forming the dress, the free edges 31a of said side portions will be united by a seam 37b in the front of the dress, and the lower edges 37c thereof will be united with the skirt 31 by the mentioned seam 35; the dress then appearing as shown in Fig. 9; the upper ends of the edges 31a and 31b being left free and not united by the seam 36, as well as the upper rear edges 37d of the waist or blouse 32 also being left free.

As will be observed, a preferably generally

circular opening 38 is arranged in the blank of the blouse 32, and the dress, in the position shown in Fig. 9, is now slipped over the head 25 of the doll body 24. Previous to this, the sleeves 34 are formed of the blanks 34a (Fig. 4) and secured to the sleeve hole or opening 34b of the blouse by an appropriate seam.

A triangular portion 33 is now bent downwardly over the front of the angel doll (Figs. 1 and 2), whereupon the waist band or belt 39 is applied and secured in the rear to the doll body 24 by a staple 40, thereby securing the dress also in a preliminary manner.

The hair of the angel doll ornament is formed of an appropriate strand of wavy, shining textile material 41, which may be cut off from a long strand thereof, indicated in an imaginary manner at 42, by the cutting lines 43, and the portion 41 appropriately arranged over the head and at the two sides of the face of my angel doll ornament, as indicated in the figures; the crown band 44 applied therearound and, then secured by any appropriate means, as by the staple 45.

The wings of my angel doll are formed of one piece of material, preferably a stamped gold or silver colored piece 46 of cardboard, and now the same will be secured to the back of the doll, as by the staples 47, thereby also finally securing the dress of my angel doll on its body 24.

Ornamental stars 49 may also be employed on various portions of the dress, and in Figs. 15 and 16 I illustrate a preferred form of securing thereof. The star 49 may be of any appropriate sheet material, preferably gilded or silver colored, and in the material of the skirt 31, and, of course, similarly in the material of the triangular portions 33, or any other part of the dress where a star is to be employed, a hole 50 will be made, a similar hole 51 being provided in the material of the star 49, whereupon a tubular, preferably metal eyelet 52 will be riveted over the parts, as indicated in Fig. 16, and as will be obvious.

As has been mentioned hereinbefore, the preferred means for removably securing my ornament on the tips of Christmas trees or their branches will be in the form of a tube 53, preferably of inexpensive cardboard. The upper portion of said tube will be pushed over the depending cylindrical extension 29 of the body 24 (Figs. 3 and 8), and it also may be secured on said depending extension by staples 54.

I may remark that all these staples may be of uniform type, as indicated at 55 in Fig. 18, and an appropriate small manual, or other, device may be employed whereby such staples may be driven into the required pieces in a quick and easy manner, as will be understood, such devices being well known in the art. The doll body 24, of course will be of such material as to permit stapling.

In Fig. 3 I illustrate the removable easy securing of my ornamental angel doll on the tip of a Christmas tree, the tube 53 simply being pulled over the top 56 of it, or of an appropriate branch of the tree, and, in a similar manner, the ornament may anytime be removed and stored for later use.

It will be understood that other suitable securing means may be employed in connection with my novel ornamental angel doll, like a helical spring, the upper end of which will engage the depending cylindrical extension 29 on the angel doll and the lower end engaging the appropriate tip of the Christmas tree or a branch

thereof, and, in a similar manner, other suitable clamping devices may be used, as will be obvious.

My ornamental angel doll may also be used at other places than on a Christmas tree, like on the wall of a room, etc.

I also employ a preferred method of mounting my angel doll for storage and shipping, as indicated in Figs. 10 and 11.

My mounting device consists of a preferably cardboard base plate 57 over the upper portion of which a transverse similar strip of material 58 is placed, and secured thereon, as by the staples 59.

The upper ends or tips 46a of the wings 46 will be pushed underneath the free ends of the strip 58 and thereupon secured by the staples 60, so that my angel doll ornament is resting on the plate 57 suspended and secured by its wings underneath the two sides of its strip 58, and in this position, it may be handled, stored, wrapped, boxed and shipped easily and safely.

When it is desired to use the ornament, staples 60 will be opened and removed, and the wings 46 pulled from underneath the strip 58.

While I have described and illustrated preferred forms and embodiments of the construction, elements, combinations, and methods of manufacturing of my novel ornamental angel doll, it will be understood that changes and variations may be resorted to in the elements, construction, combination and processes thereof, and I reserve my rights to all such changes and variations which are within the spirit of this specification and the scope of the claims hereunto appended.

Such variations and changes may consist in dyeing the hair to different colors, preferably blonde and using for the dress of my ornamental doll, printed silk of appropriate design and color effect.

What I claim as new and want to protect by Letters Patent of the United States, is:

1. In an ornament for Christmas trees, having a doll body, and a dress secured on the body, a dependent extension on said body, a tubular member, one end adapted to be pushed over said extension and the other over the tip of a Christmas tree, for securing said doll on said tip, said extension and said tube being concealed by said dress.

2. In an ornament for Christmas trees, having a doll body, and a dress secured on the body, a dependent extension on said body, and securing means adapted to engage said extension and the tip of a part of a tree, respectively, the material of the body being adapted to be penetrated by usual staples, and said securing means and said dress being attached to the body by stapling.

3. In an ornamental doll for Christmas trees, having a doll body, and a dress on said body, including a skirt portion, a blouse portion and a triangular extension on said blouse adapted to be pulled over the head of the doll to the front thereof and over said waist and said skirt, a belt for the waist of the dress passed over said triangular extension, said body being of a material adapted to be penetrated by the usual staples, and staples for securing said belt and said triangular extension on the body, thereby also securing said dress.

4. An ornamental doll for Christmas trees, having a doll body with a head, a dress on said body, including a skirt portion, a blouse portion and a triangular extension on said blouse adapt-

ed to be pulled over the front thereof, a belt for the waist of the dress and over said triangular extension, said body and head being of a material adapted to be penetrated by the usual staples, and staples for securing said belt on the body, thereby also securing said dress, a plate element forming two wings secured on the back of the body over said blouse by staples to give

an angel-like appearance to said ornamental doll and to further secure the dress on the body, a strand of textile threads arranged on said head to imitate the hair thereon, a band around said head, and the hair thereon, and a staple to secure said band on said head and said hair there-through.

JOSEPH REICH.
